UNITED STATES PATENT OFFICE

GEORGE HERBERT PADGHAM, OF LONDON, ENGLAND

ROTARY DUPLICATOR

Application filed April 30, 1929. Serial No. 359,220.

This invention relates to rotary duplicators having perforated or like foraminous stencil-carrying cylinders, belts or similar stencil supporting media, and has for its object to 5 provide improved means for feeding paper into the machine.

Paper from a pile is fed towards the cylinder by advancing that sheet which, for the time being, is uppermost, by means of a reciprocating carriage, which is spring influenced in the feeding direction and adapted to be forced back against the spring action by link and lever mechanism operated by a cam on the cylinder spindle. A cross-bar mounted 10 on two side frames of the reciprocating carriage supports a plurality of contact fingers, each furnished with india-rubber or like pads, adapted to bear on the surface of the paper, said fingers being inclined downwardly and 15 towards the cylinder, so that as said cross-bar is advanced towards the cylinder, the friction between said pads and the paper causes the uppermost sheet to advance until its leading edge enters between the cylinder 20 and a pressure roller therebeneath. During the return motion of the reciprocating carriage the pads or the like slide freely over the uppermost sheet of paper, in readiness to feed forward the succeeding sheet. When 25 the fingers are inclined downwardly at an angle of about 45° to the paper, the forward thrust on the uppermost sheet of paper is most effective, and said sheet is fed forward with surety. For other angles, i. e. for too 30 great an angle the friction between the pads and the paper may be so great that no motion can take place, while if the angle be too small, the friction may not be sufficient to move the paper, the pads sliding idly over 35 the surface thereof. In order, then, to ensure that the fingers occupy this most efficient position, an object of the invention is so to arrange the paper-carrying means relatively to the contact fingers, that the uppermost sheet 40 may be brought to the required level, whatever may be the thickness of the pile of paper (within the limits of the machine) whilst, when the machine is in use, it is desirable that the uppermost sheet of paper should always 45 be at substantially the same level, hence, as

each sheet is advanced the pile of paper should be raised. It is, therefore, a further object of the invention to provide means whereby the table, supporting the pile of paper, may be raised step-by-step after each 55 sheet has been fed forward, through a distance substantially equivalent to the thickness of a sheet of paper, in order that the fingers may remain inclined at the angle which gives the best result.

A further object of the invention is to provide means whereby the feeding of the paper to the machine is automatically and reliably stopped when a certain number of 60 sheets has been fed thereto.

Another object of the invention is to ensure that the reciprocating carriage shall not be advanced when the contact-fingers have been moved to their inoperative position and a still further object of the invention is to 70 provide, on the reciprocating carriage, a plurality of contact-fingers any number of which may be used at a time, for the purpose of obtaining the necessary thrust on the paper, whether it be thick or thin and whether it 75 possesses a smooth or a rough surface.

According to the present invention the paper to be fed to the cylinder is supported upon a table adapted to be slidden vertically by means of lifting mechanism. This lifting mechanism may be in the form of a rotary cam or cams or in some cases one end of the table may be raised by a rotary cam or cams and the other end by a lever or levers actuated by a cam or the like. Preferably the 80 lifting mechanism is adapted to be set to adjust the level of the paper initially and thereafter to be actuated step-by-step as the sheets of paper are fed successively to the cylinder. For this purpose the cams may be 85 secured to a rotary shaft adapted to be controlled by ratchet and pawl mechanism and furnished with an operating handle so that, after the pawl has been disengaged from the ratchet, said shaft may be turned initially 90 to adjust the level of the paper, whilst a second pawl reciprocated by the reciprocating carriage is adapted to advance said shaft step-by-step through the ratchet wheel as 95 the machine is operated.

In order to obviate the necessity of counting the number of sheets passing through the machine, an indicating finger may be set to any required number and clamped to a disc driven concurrently with the cylinder, whilst a pawl adapted to co-operate with a rack on, or movable with, the reciprocatory carriage is held, normally, out of engagement with said rack by a catch resting on a stop and adapted, when the predetermined number of sheets of paper has passed through the machine, to be engaged by said indicating finger and to be disengaged from said stop thereby permitting the pawl to engage 10 the rack and prevent further reciprocation of the carriage.

In order to lock-up the reciprocatory carriage when the contact fingers are in their inoperative position, said fingers are pivotally mounted and a bar extending transversely therebeneath is carried by a lever in one with a cross bar, one end of which is stepped, and a notched plate on a fixed part of the machine is so located relatively to said stepped end that in one angular position of said cross bar (to which position said cross bar may be moved by actuation of its lever), the stepped end will pass clear of said notched plate, while in another angular position of said cross bar, and when the reciprocatory carriage is at the rear end of its travel, said stepped end will engage in the notch of the plate and prevent reciprocation of the carriage.

In order that the friction between the contact fingers and the uppermost sheet of paper may be varied to suit requirements, said fingers may be pivoted individually on said cross bar so that any one or more may be thrown back to an inoperative position.

One form of rotary duplicator constructed in accordance with the invention is illustrated by the accompanying drawings, wherein Figure 1 is a plan view of a portion of the cylinder; Figure 2 is a similar view, shewing the parts in a different position; Figure 3 is a cross-section of a detail on the line 3—3 of Figure 1; Figure 4 is a sectional plan to illustrate the operative connections, the cylinder being omitted; and Figures 5 and 6 are side elevations, one from the right and the other from the left, parts being broken away in both views for the sake of clarity; Figure 7 is a fragmentary view of the contact fingers in their inoperative position; Figure 8 is a fragmentary view of means for preventing the pressure roller from becoming soiled by contact with the inking surface of the cylinder, whilst Figure 9 is a fragmentary isometric view to an enlarged scale of part of the mechanism shown in Figure 5, with parts broken away for the sake of clarity.

As shown in Figures 1, 2 and 3, a stencil 11 is formed with a number of perforations 15 in order that one end thereof may be engaged

with a series of pins 12, in a recess in the periphery of a cylinder 13, (Figures 1, 2, 3, 5 and 6). To the ends of said cylinder 13 and adjacent to the recess in which are situated the pins 12, are secured guide strips 14 to provide guideways for an arcuate plate 15, the surface of which may be roughened by the attachment thereto of emery-cloth or the like, said plate 15 being thus adapted to be slidden back to uncover the pins 12, as shewn in Figure 2, when it is desired to attach a stencil 11, and to be slidden thereafter into its normal position as shewn in Figure 1, and said plate 15 is so situated relatively to the cylinder 13 and its associated parts, that the leading edge of the paper which is to be printed comes into contact with the roughened surface of the plate 15, as it is fed forward to the cylinder 13, said roughened surface thus preventing relative movement between the contacting surfaces of the cylinder and paper.

A pile of the paper to be printed is stacked upon a supporting table 16, adapted to be mounted detachably and adjustably with respect to the cylinder 13, as will be hereinafter described. The table 16 is provided with side-gripping devices 17, 18 of known type, and a gauge 19 for the rear edge of the paper which is fed towards the cylinder 13, while a roughened surface 16^a is provided thereon, for the purpose of preventing the actuation of the contact fingers, after the last sheet of paper has been fed to the printing cylinder. The cylinder 13 is rotatably mounted on a spindle 20 secured to the side frames 21, 22, and may be caused to rotate by means of the crank-handle 23, attached on the outside of the side frame 21, to a spindle, to the inner end of which is secured a toothed wheel 24 adapted to engage with a similar toothed wheel 25 attached to the cylinder 13 on the spindle 20.

For the purpose of advancing the sheet of paper, which for the time being is uppermost on the pile on the table 16, a reciprocatory carriage is provided, consisting of two side members 26, 27, mounted on the ends of horizontal bars 28, 29, the bar 29 forming also a support for a number of contact fingers 30 rotatably mounted on a bar 31 which is itself rotatable on the side-members 26, 27, and resilient pads 32 of rubber or the like attached to the ends of said fingers being adapted to press on the surface of the uppermost sheet of paper. These fingers are adapted to be swung out of contact with the paper, i. e. swung to an inoperative position, by means of a single thumb-lever 33, in the form of a bell-crank lever to one end of which is secured a bar 34 arranged to press on the undersides of the fingers 30 to swing them to the inoperative position, as shown in Figure 7. The extent of the swing-back of the

fingers is determined by the horizontal bar 28 which acts as a back-stop therefor.

It is found that the most suitable force is exerted on the paper to feed it to the cylinder 13 when the fingers 30 are set at an angle of about 45° with respect to the horizontal, and in order to ensure that the fingers will take up this position, the bar 29 is provided, which acts as a front stop therefor, and determines the extent of the forward and downward swing of the fingers 30.

Motion is imparted to the reciprocating carriage by means of a pair of horizontal links 35, 36, pivoted at their front ends to lugs 37, 38, projecting from the side members 26, 27, and passing through slots 39, 40, formed in a pair of auxiliary side frames 41, 42 securely attached to the main side frames 21, 22. The side members 26, 27 are arranged to reciprocate along pairs of horizontal guide bars 43, 43 and 44, 44, integral with the auxiliary side frames 41, 42. The rear ends of the horizontal links 35, 36 are pivoted at 48, 49 to oscillating levers 45, 46, pivoted at their lower ends to a transverse bar 47, secured to the side frames 21, 22. The lever 46 is in the form of a bell-crank lever, and to the other arm 50 of this lever is attached a tension spring 51, the other end of which is attached at 52 to the side-frame 22. In this manner the reciprocating carriage is spring-influenced so that its side members 26, 27, and hence the bar 31 carrying the fingers 30, tend to move towards the cylinder 13, reverse movement is imparted to the reciprocating carriage by means of a cam 53 on the spindle 20 of the cylinder 13, which cam is arranged to coact with an anti-friction roller 54 on a thrust-rod 55, the lower end of which is forked to engage a pin 56 on the arm 50 of the bell-crank lever 46, 50, and the upper end of which is bifurcated as at 57 and guided by the bearing 58 for the cylinder spindle 20. When the reciprocating carriage is locked against movement, as will be described hereinafter, the thrust rod 55 remains in its lowermost position and unaffected by the action of the cam 53 when the cylinder 13 is rotated. In order to lock the reciprocating carriage against motion, when all the fingers 30 are in the inoperative position as shown in Figure 7, one end of the bar 31 projecting beyond the side-member 27 is cut away as at 59 so as to be adapted to pass clear of a plate 60, adjustably attached by pins 61 operating in slots 62, to the side member 42, so that when the fingers 30 are swung back by the lever 33, and bar 34, as shown in Figure 7, the rounded portion of the projecting end of the bar 31 engages a notch 63 in the plate 60 and the carriage is thereby prevented from moving towards the cylinder 13.

When the reciprocating carriage is unlocked and the cylinder 13 is caused to rotate,

by rotation of the crank-handle 23, the pads 32, pressing on the uppermost sheet of paper of the stack, will cause this sheet to be fed towards the cylinder from between the gripping devices 17, 18, until its leading edge enters between the cylinder 13 and a pressure roller 64 therebeneath, the roughened surface of the plate 15 being at this moment immediately opposite said pressure roller owing to the setting of the cam 53 relatively to said cylinder. The sheet of paper is given a slight upward tilt by means of an inclined plate 65 rigidly attached to the base 66, just before its leading edge is engaged by the roughened surface of the plate 15, thereby ensuring a smooth passage of the sheet between the cylinder and the pressure roller 64. This roller 64 is carried in bearings at the free-ends of the substantially horizontal arms 67, 68 of bell-crank levers pivoted to the transverse cross bar 69, whilst to the other arms 70, 71 of said bell-crank levers are secured pins 72, 73, adapted to carry a transverse flat bar 74, said bar being slidable along said pins against the action of springs 75, 76. A cam 77 mounted on a cross bar 78, acts against the flat-bar 74, and rotation of said cam forces the bar 74 against the springs 75, 76 and thus rocks the bell-crank levers 67, 70 and 68, 71 thereby lifting the pressure roller 64. This is for the purpose of varying the pressure between the roller and the cylinder 13. To one end of the cross bar 78 is attached an arcuate ratchet 79 adapted to be engaged normally by a pawl 80. The ratchet is rotated by means of a lever 81 splined on the end of the cross bar 78, outside the side frame 21. By rotating this lever in a clockwise direction (Figure 5), the cam 77 may be caused to rotate step-by-step, to raise the pressure roller 64 correspondingly, and is maintained in any one of its positions by means of the pawl 80, and in order to return the cam 77 and hence the pressure roller 64 to normal position, a spring-influenced push-button 82 is provided to disengage the pawl 80 from the ratchet 79, to permit the pressure roller to return to its lowermost position partly due to gravity and partly due to the pressure of the springs 75, 76.

In order to move the pressure roller 64 away from the cylinder 13 against the action of the springs 75, 76, a cam 83 is mounted on the cylinder 13 and is adapted to coact with an antifriction roller 84 on a thrust rod 85, pivotally connected at its lower end with an arm 86 at one end of a horizontal cross-bar 87, and is guided at its upper end by an arm 88 thereon engaging the bearing 89 of the cylinder spindle 20. The upper end of the thrust rod 85 is also supported by a link 90, pivoted at one end to said thrust rod and at the other end to the side-frame 21. Projecting from the cross-bar 87 are a pair of lugs 91, 92 (Figure 4) adapted to press from above

against the ends of the arms 67, 68 of the bell crank levers supporting the pressure roller 64 to force said levers downwards. Downward movement of the thrust-rod 85, due to the action of the cam 83 and the antifriction roller 84, as the cylinder 13 is rotated, causes the arm 86 to be depressed, thereby rocking the cross-bar 87, and causing the lugs 91, 92 to press the arms 67, 68 of the bell crank levers downwards to shift the pressure roller 64 out of contact with the cylinder 13.

In order to prevent the pressure roller 64 from being pressed against the cylinder 13 when the latter is rotated but when the reciprocating carriage is locked or does not advance fully there-towards, a stop-lug 85^a projects outwardly from the thrust rod 85, whilst pivoted to a lug 85^b projecting inwardly from the side-frame 21 is a notched plate 85^c which under the action of a spring 85^d also anchored to the side-frame 21, lies normally in the path of the stop lug 85^a, and thus is adapted to prevent upward movement of said thrust rod 85. A lug 85^e projecting outwardly from the notched plate 85^c, lies in the path of a downwardly and inwardly projecting plate 35^a secured to the horizontal bar 35 which, just at the end of the forward travel of the reciprocating carriage, engages the lug 85^e and disengages the notch in the notched plate 85^c from the stop-lug 85^a. The movements of the parts of the machine are so co-ordinated that this disengagement takes place when the cam 83 is not exerting any thrust on the thrust-rod 85, whereupon the pressure roller 64 has permitted to be pressed upwards towards the cylinder 13. Hence, as the pressure roller 64 cannot be moved upward unless the carriage has been advanced fully, and as the carriage 40 cannot be moved forward either when the last sheet of paper has been fed forward, or when the required number of sheets of paper has been fed forward, (the reciprocating carriage being then locked by means of the pawl 149, as will be described hereinafter), it follows that the pressure roller 64 cannot be pressed upward against and be soiled by contact with, the inking surface of the cylinder 13.

50 The supporting table 16 is adapted to be raised or lowered according as a thin or thick pile of paper is to be fed to the printing cylinder, so that the uppermost sheet of paper may be presented at such a level relatively to the rod 31 on which the fingers 30 are pivoted that said fingers make with said paper substantially the most effective angle for feeding the paper to the cylinder 13. In order that this effective angle may be maintained, it is obvious that the supporting table must be raised, after each sheet of paper has been fed forward, by an amount substantially equivalent to the thickness of the sheet.

For this purpose the table 16 is provided 65 with transversely disposed lugs 93, 94, to-

ward that edge thereof nearer the cylinder 13, adapted to slide in vertical grooves 97, 98, the table being supported on a pair of cams 99, 100 and a horizontal cross-bar 101 interconnected therewith and extending towards the rear end of said table, (see Figures 5 and 6). The cams 99, 100 are fixedly mounted on a transverse cross-bar 102 carried in bearing brackets secured to the base 66 of the machine. Mounted fixedly and eccentrically on the cross-bar 102 adjacent each cam is an eccentric sheave 105, supporting an eccentric strap 106 so that rotation of the cross-bar 102 imparts a lifting motion to the straps 106. Secured by pins 108 to the lower points of the straps 106 are levers 110, 111, extending towards the rear of the machine, and pivoted by pins 112, 113 to lugs 114, 115 secured to the base 66. The forward ends of the levers 110, 111 are extended, and pivotally secured to the ends thereof by a transverse bar 116 is the U-shaped bar 117, 101, 118, the portion 101 lying transversely and forming the back rest for the table 16 as set forth above. The portions 117, 118 may be given an upward bend to ensure that the portion 101 lies substantially in the same horizontal plane as the upper faces of the cams 99, 100. The portions 117, 118 are extended beyond the pivot 116 and formed with recesses, adapted to engage with pins secured to the inner faces of the levers 110, 111, which provide a back-stop for the portion 117, 101, 118 of the table rest. It will be seen, therefore, that when the cams 99, 100 rotate, the levers 110, 111, 90 will be lifted, swinging about their pivots 112, 113, due to the lift imparted by the eccentric sheaves 105, and hence the bar 101 will be lifted correspondingly, in such a manner that the plane through the upper faces 95 of the cams 99, 100 and the bar 101, i. e. the plane of the table 16 remains substantially horizontal.

Fixed to rotate with the cross-bar 102 is a toothed wheel 121, Figure 9, the teeth of which are in engagement permanently with a pinion wheel 122, mounted on a spindle 123 between the side-frame 21 and a bracket 124 secured to the base 66. Also on the cross-bar 102, but outside the side-frame 21 is a hand-lever 125 for the purpose of manually adjusting the position of the cams 99, 100, and the bar 101 and hence the vertical distance of the table 16, from the cross-bar 31. This is necessary, in order that stacks of paper of different quantity may be placed initially on the table 16. On the spindle 123 are mounted two further toothed wheels 126, 127, the one, 126, being a ratchet-toothed wheel and being engaged by a ratchet device 125 for a purpose which will be set forth hereinafter, the other, 127, being engaged by a larger toothed wheel 128 mounted on a spindle 129, between the side frame 21 and the bracket 124. On the spindle 129 and out- 130

side the side-frame 21, is a circular disc 130, adapted to follow-up the rotation of the toothed-wheel 128, while an arm 131 loosely mounted on the spindle 129 is adapted to be clamped to the disc 130 by means of the clamping screw 132. The outer end of the arm 131 is formed in the shape of a pointer which slides over a fixed annular disc 133 for a purpose set forth hereinafter.

Engaging the ratchet wheel 126 is a sliding pawl 134, connected with a horizontal link 135, slidably pivoted at 136 to the side-frame 21. This link is adapted to be held in its rearward position (to the right, Figures 5 and 9) by means of a spring 137, while a portion thereof is cut away to form a longitudinal recess 138. A pin 139 on the oscillating lever 45 operates in the recess 138 so as, by engaging one end thereof to force the link 135 against the tension of the spring 137, thereby causing the sliding pawl 134 to effect a rotation of the ratchet wheel 126 through a predetermined angle. Rotation of the ratchet wheel 126 imparts rotation to the pinion 122 which, in turn, imparts rotation to the toothed wheel 121 on the cam cross-bar 102, while the toothed wheel 127 rotates as one with the ratchet wheel 126. The toothed wheel 127 imparts motion to the toothed wheel 128 and hence to the disc 130. It will be clear that rotation of the toothed wheel 121 causes the cross-bar 102 to rotate and hence the cams 99 and 100 are moved angularly and the cross-bar 101 is raised or lowered through a distance corresponding with the angular displacement of the wheel 121. Thus for each movement of the reciprocatory carriage, i. e. for each to-and-fro oscillation of the link 45, the cams 99 and 100 and the cross-bar 101 are given a small angular displacement and a small lift respectively, with the result that the supporting table 16 is lifted a small amount after each sheet of paper is passed between the printing cylinder 13 and the pressure-roller 64. The ratchet wheel 126 is prevented from rotating in the reverse direction due to the force exerted thereon by the weight of the table 16 and the paper supported thereby after each movement of the sliding pawl 134, by a pawl lever 141 engaging said wheel, which pawl may be disengaged therefrom by means of a manually operable lever 142, when it is desired to allow the table to return to normal position. The lever 142 may also be pressed when it is desired to set the table rapidly and noiselessly initially by means of the manual lever 125.

Means are provided to stop the operation of the reciprocatory carriage automatically after a predetermined number of sheets of paper have been printed. For this purpose, the annular disc 133 is suitably graduated to indicate quantities of paper. The arm 131 is clamped to the disc 130 by means of the

clamping screw 132, so that the pointer registers with the number on the disc 133 corresponding with the number of sheets of paper it is desired to print. As the cylinder is rotated the pinion wheel 122 is rotated, and the table 16 is raised, as previously described, while the toothed wheel 128 and hence the disc 130 and pointer 131 is rotated step-by-step as each sheet of paper is printed. When the pointer 131 comes to the zero position, which in the example shown is the highest point of the disc 133, the end of the pointer 131 engages a latch 144, normally maintained in inoperative position by means of a lug 145 on the side-frame 21 being held in engagement with said lug by means of a spring to cause it to disengage said lug and to drop under gravity. The latch 144 is pivoted at its upper end at 146 to an arm 147, pivoted on a spindle 148 passing through the side-frame 21. On the spindle inside the side frame 21, and immediately above the link 35 is a second arm or pawl lever 149 which is adapted, when the latch 144 is disengaged from the lug 145, i. e. when the spindle 148 is rotated, to drop into engagement with one of a series of notches 150 formed in the upper edge of the link 35, thereby preventing said link from reciprocating as the cylinder 13 is rotated. In this manner the feed of further sheets of paper to the cylinder is stopped.

I claim:—

1. In a sheet feeding and separating device for a rotary duplicator having, a printing cylinder, and means for rotating said printing cylinder, a reciprocatory carriage for feeding sheets of paper successively to said printing cylinder, spring mechanism for actuating the reciprocatory carriage in the feeding direction, link and lever mechanism for actuating said reciprocatory carriage in the reverse direction, means comprising cam mechanism operated by rotation of said printing cylinder, for actuating said link and lever mechanism, a supporting table and rotary cam mechanism for initial adjustment of the level of said table and for raising said table successively step-by-step vertically after each sheet of paper has been fed forward to said printing cylinder.

2. In a sheet feeding and separating device for a rotary duplicator having, a printing cylinder, and means for rotating said printing cylinder, a reciprocatory carriage for feeding sheets of paper successively to said printing cylinder, spring mechanism for actuating the reciprocatory carriage in the feeding direction, link and lever mechanism for actuating said reciprocatory carriage in the reverse direction, means comprising cam mechanism operated by rotation of said printing cylinder, for actuating said link and lever mechanism, a supporting table and rotary cam mechanism for initial adjust-

ment of the level of said table and for raising said table successively step-by-step vertically after each sheet of paper has been fed forward to said printing cylinder, said cam mechanism acting on the forward end of said table, and lever mechanism acting on the rearward end of said table when said cam mechanism acts on the forward end of said table.

10 3. In a sheet feeding and separating device for a rotary duplicator as claimed in claim 2, cam mechanism for actuating the lever mechanism which acts on the rearward end of said table.

15 4. In a sheet feeding and separating device for a rotary duplicator having, a printing cylinder, and means for rotating said printing cylinder, a reciprocatory carriage for feeding sheets of paper successively to said printing cylinder, spring mechanism for actuating the reciprocatory carriage in the feeding direction, link and lever mechanism for actuating said reciprocatory carriage in the reverse direction, a paper supporting table, means comprising ratchet and pawl mechanism for raising said table successively step-by-step as each sheet of paper is fed forward to said printing cylinder.

20 5. In a sheet feeding and separating device for a rotary duplicator as claimed in claim 4, means actuated by the rotation of the printing cylinder for actuating said ratchet and pawl mechanism.

25 6. In a sheet feeding and separating device for a rotary duplicator having, a printing cylinder, and means for rotating said printing cylinder, a reciprocatory carriage, spring mechanism for actuating said reciprocatory carriage in the feeding direction, link and lever mechanism for actuating said reciprocatory carriage in the reverse direction, a stop device, and means for actuating said stop device to stop the operation of the reciprocatory carriage when a predetermined 30 number of sheets of paper has been fed to said printing cylinder.

35 7. In a sheet feeding and separating device for a rotary duplicator as claimed in claim 6, a graduated disc, a pointer actuated 40 concurrently with the rotation of the printing cylinder, and passing over said disc, a catch pivoted on a lever and normally supported on a lug, said lever being mounted on a spindle, a pawl on said spindle, a series of 45 notches in one of the levers of the link and lever mechanism for actuating said reciprocatory carriage in the reverse direction, said pawl being adapted to engage said notched lever and said pointer being adapted to dis- 50 engage said catch from said lug when said pointer is in a predetermined position, said pawl being thereby permitted to engage said notched lever to stop the operation of said reciprocatory carriage.

65 8. In a sheet feeding and separating de-

vice for a rotary duplicator having, a printing cylinder, and means for rotating said printing cylinder, a reciprocatory carriage for feeding sheets of paper successively to said printing cylinder, a plurality of contact fingers on said reciprocatory carriage pressing on the sheet of paper which for the time being is uppermost, friction means on said contact fingers, means for maintaining said fingers inclined downwardly and towards 70 said printing cylinder at a predetermined angle, means for moving said fingers to an inoperative position, and means for locking said reciprocatory carriage against motion when said fingers have been moved to an inoperative position.

75 9. In a sheet feeding and separating device for a rotary duplicator as claimed in claim 8, means for moving said contact fingers individually to an inoperative position.

80 10. In a sheet feeding and separating device for a rotary duplicator having, a reciprocatory carriage, a plurality of contact fingers on said carriage, friction means on said contact fingers, means for moving said contact fingers to an inoperative position, a cross-bar supporting said fingers formed with a stepped end, a notched plate fixed relatively 90 to said reciprocatory carriage, said notched plate being engaged by the stepped end of said cross-bar when the contact fingers are moved to an inoperative position to prevent the reciprocation of said reciprocatory carriage.

95 11. In a sheet feeding and separating device for a rotary duplicator as claimed in claim 8, a bar extending transversely beneath the contact fingers and a hand lever for actuating said bar to move said contact fingers to an inoperative position.

100 12. In a sheet feeding and separating device for a rotary duplicator having, a printing cylinder, and means for rotating said printing cylinder, a reciprocatory carriage for feeding sheets of paper successively to said printing cylinder, a paper supporting table, a roughened surface on part of said cylinder, and a roughened surface on part of said table.

105 13. In a sheet feeding and separating device for a rotary duplicator having, a printing cylinder, and means for rotating said printing cylinder, a reciprocatory carriage for feeding sheets of paper successively to said printing cylinder, a paper supporting table, manually operable means for initial adjustment of the level of said table, means for raising said table step-by-step successively as each sheet of paper is fed to said printing cylinder, means for preventing the operation of the reciprocatory carriage when a predetermined number of sheets of paper has been printed, contact fingers on said reciprocatory carriage, friction means on said contact fin- 115

gers, means for moving said contact fingers individually to an inoperative position, and means for preventing the operation of said reciprocatory carriage when all of said contact fingers are moved to an inoperative position.
